BLADE GUARD FOR FAN

Robert S. Knapp, St. Louis, Mo., assignor to Knapp-Monarch Company, St. Louis, Mo., a corporation of Delaware

Filed Apr. 2, 1962, Ser. No. 69,540

Term of patent 14 years

(Cl. D62—4)

FIG. 1 is a perspective view of a blade guard for a fan showing the new design;

FIG. 2 is a side elevational view of the same; and

FIG. 3 is a front elevational view of the same.

I claim:

The ornamental design for a blade guard for fan, substantially as shown and described.
